CLAIM

The ornamental design for a wax melting lamp, as shown and described.

DESCRIPTION

FIG. 1 is a top, front and right-side perspective view of the wax melting lamp showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is bottom, rear and left-side another perspective view thereof; and,

FIG. 9 is an enlarged view, of circled portion 9, of FIG. 1, thereof.

The broken lines throughout the drawing figures depict portions of the wax melting lamp that form no part of the claimed design.

The dot-dash broken lines depict the boundaries of the FIGS. 1 and 9 enlargement that forms no part of the claimed design.

1 Claim, 9 Drawing Sheets
